ATTORNEYS

UNITED STATES PATENT OFFICE

ADIEL Y. DODGE, OF SOUTH BEND, INDIANA, ASSIGNOR TO BENDIX BRAKE COMPANY,
A CORPORATION OF ILLINOIS

BRAKE MECHANISM

Original application filed October 8, 1924, Serial No. 742,282. Divided and this application filed May 16, 1928. Serial No. 278,155.

My invention relates to improved brake mechanism and is embodied in a brake structure comprising a plurality of pivotally connected internal brake shoes supported within a rotatable brake drum to be urged thereagainst in such a manner that one shoe is adapted to energize the other depending upon the direction of rotation of the drum and the shoes are urged against the drum by operating mechanism of a novel character adapted to float to adjusted positions during the application of the shoes to the drum.

A further object resides in a novel method of supporting shoes to be urged against the drum in combination with the mechanism employed to apply them to the drum.

This application is a division of my parent application, Ser. No. 742,282, filed October 8, 1924, now Patent Number 1,705,855, dated 20 March 19, 1929.

Other advantages and meritorious features will more fully appear from the following description, appended claim and accompanying drawing, wherein—

25 Fig. 1 is a vertical sectional view through a brake drum showing my shoes and operating mechanism in side elevation.

In the drawing let 10 indicate a rotatable 30 brake drum within which are mounted two substantially inflexible arcuate brake shoes 12 and 16 pivotally connected by a pivot 14, carried by a link 50 mounted upon a pivot 52 carried by the backing plate 54.

The opposite ends 22 and 26 of the shoes 35 are slotted as at 24 and 28 to receive stationary anchors 18 and 20 carried by the backing plate. These anchors serve to anchor the shoes depending upon the direction of rotation of the drum. When the drum is rotating in a clockwise direction, anchor 20 engages shoe 16 to anchor the shoes therein and shoe 12 travels over its anchor 18 urging the shoe 16 against the drum. When the drum is traveling in the opposite direction the shoes 40 anchor upon the member 18 in a similar manner.

Shoe 12 is provided at its extreme free end with a bearing roller 30 and shoe 16 is provided at its extreme free end with a bearing 45 roller 32. The spring 48 tensions the shoes

toward each other. 58 represents an adjustable stop device.

To operate the shoes I provide a floating wedge member 34 pivotally supported at 36 upon a bell crank lever 38 mounted upon a pivot 40 carried by the backing plate and having its opposite arm 42 pivotally connected at 44 to a link 46 whereby the wedge member is moved between the shoes bearing against the rollers 30 and 32 to urge the shoes outwardly against the drum. This wedge member is adapted to travel over the anchored shoe urging the unanchored shoe outwardly.

What I claim is:

Brake mechanism comprising, in combination with a rotatable brake drum, substantially inflexible brake shoes pivotally connected one to another said shoes arranged within the drum and having spaced apart free separable slotted ends, an anchor arranged within each slotted end to take the torque of the adjacent shoe when the drum is turned in one direction, said shoe adapted to travel over said anchor when the drum is turned in the opposite direction to urge the anchored shoe against the drum, operating mechanism including a floating wedge adapted to be urged between the free ends of said shoes and a pivotally supported link carrying at its free end the pivotal connection for said shoes, said link together with the anchors providing a three-point support for the brake shoes.

In testimony whereof I, ADIEL Y. DODGE, sign this specification.

ADIEL Y. DODGE.
